UNITED STATES PATENT OFFICE.

ROBERT ARTHUR SMITH, OF LONDON, AND THOMAS MEACOCK, OF SOUTHEEND-ON-SEA, ENGLAND.

CRANE FOR LIFTING, LOWERING, AND TRANSPORTING LOADS.

Application filed October 15, 1923, Serial No. 668,720, and in Great Britain October 31, 1922.

This invention relates to cranes of the kind comprising a luffing jib and winding gear mounted on a wheeled carriage provided with a motor and steering devices so that the carriage can be driven from place to place on ordinary road surfaces.

With this type of travelling crane, a load carried by the jib has a tendency to tilt the carriage, and in the constructions heretofore provided, since the pivotal support of the jib occupies a fixed position, the tilting moment applied to the carriage progressively increases as the jib is lowered about its pivotal support, that is to say, as it approaches a horizontal position.

This invention provides an improved construction of automobile crane in which the radius at which the tilting force acts is kept substantially constant for all positions of the jib within a wide angle of movement. The improved crane is thus especially adapted for use in cases where it is required to lower the jib whilst a load is suspended thereon, for example, in order that the crane may be able to pass through a doorway or beneath an arch before depositing its load.

In order to obtain this result, the pivotal support of the jib is carried by a frame movable along a guideway or track on the carriage, and a guide pin or roller carried by the jib, or an extension thereof, is arranged to travel on a cam path, the paths of the pivot frame and the roller being correlated in such a manner that, when the jib is raised to its highest position the frame is near one end or side of the carriage, and in order to lower the jib towards a horizontal position the frame must be moved rearwardly or towards the opposite side or end of the carriage.

The said pin or roller may be arranged between the head of the jib and its pivotal support, or it may be arranged on an extension of the jib projecting forwardly or rearwardly at any desired angle, the cam path for this pin or roller being appropriately situated above or below the guideway or track for the pivot frame. The frame carrying the pivotal support of the jib, and, in some cases, the pin or roller also, may be moved along their respective paths by a nut and screw rack and pinion or like mechanism driven through worm and worm-wheel, bevel or like gearing.

In the accompanying drawing which

shows how the said invention may be conveniently and advantageously carried into practice:

Figure 1 is a side view, and

Figure 2 a plan of an automobile crane 60 constructed in accordance with this invention, and Figure 3 is a detail view of parts of the improved crane.

As shown in this drawing, 1 is an under carriage carried on road wheels 2 driven 65 through a shaft 3 and steered by a rod 4. A carriage 5 mounted on a turntable support 6 on the undercarriage 1 carries a suitable motor 7 geared to the shaft 3 and to gearing 8 by which the carriage 5 may be 70 rotated on the undercarriage 1.

A jib 9 is pivotally mounted on a shaft 10 carrying pinions 11 which are arranged to travel along inclined racks 12. Extensions 13 of the jib 9 carry rollers 14 which travel 75 along cam paths 15 inclined to the racks 12. From a consideration of Figure 1 it will be apparent that, when the shaft 10 is at the right hand end of the racks 12, the jib will be supported in the raised position, shown 80 in full lines, by the extensions 13 and rollers 14 bearing against the cam paths 15, and, when the shaft 10 is at the left hand end of the racks 12, the jib will be lowered to the position indicated in broken lines. Whilst the jib is moving between these two positions the jib head 9a will move along a substantially vertical line so that the tilting movement exerted on the carriage by a load carried on the jib will remain practically 85 90 95 constant since the radius at which it acts is not substantially changed.

The shaft 10 is mounted in frame part 16 slidable along shafts 17 driven by the motor 7 through the shafts 18 and reversing 100 clutches 19. Worms 20 respectively rotating with the shafts 17 and slidable thereon are held within the said frame parts 16. One of these worms is in gear with a worm wheel 21 keyed to the shaft 10 to drive the pinions 11 and the other worm is in gear with a worm wheel 22 coupled to a winding drum 23 mounted on the shaft 10 coaxially with the pivotal support of the jib.

We claim:—

1. A crane comprising a jib, a movable frame on which said jib is pivotally supported, a roller on the said jib spaced apart from the pivotal support of the jib, a guide track for the said roller, a winding drum 110

carried on the said movable frame, driving shafts on which the movable frame is slidably mounted, and gearing transmitting motion from the said shafts to the movable frame and winding drum, respectively.

2. A crane comprising a jib, a frame on which the jib is pivotally supported, an extension of the jib carrying a roller, a guide track for the roller arranged divergently with respect to the path of the said frame, a winding drum carried on the said frame, driving shafts on which the movable frame is slidably mounted, and gearing transmitting motion from the said shafts to the movable frame and winding drum, respectively.

3. A crane comprising a carriage, a jib, a frame on which the jib is pivotally supported, a roller on the said jib spaced apart from the said pivotal support of the jib, a guide track for the said roller, a motor on the carriage, a winding drum carried on the said frame, driving shafts geared to the said motor and having the said frame slidably mounted thereon, and gearing transmitting motion from the said shafts to the frame and winding drum, respectively.

4. A crane comprising a carriage, a jib, a frame on which the jib is pivotally supported, a roller on the said jib, and a guide track for the said roller arranged divergently with respect to the track along which the frame is movable, a motor on the carriage, a winding drum carried on the said frame, driving shafts geared to the said motor and having the said frame slidably mounted thereon, and gearing transmitting motion from the said shafts to the frame and winding drum, respectively.

5. A crane comprising a carriage, an under carriage, a turntable support on the under carriage on which the carriage is mounted, a jib, a frame on which the jib is pivotally mounted, a roller on the jib spaced apart from the pivotal support of the said jib, divergent tracks on the carriage along which the frame and roller are respectively movable, a motor on the carriage, a winding drum carried on the said frame, driving shafts geared to the said motor and having the said frame slidably mounted thereon, and gearing transmitting motion from the said shafts to the frame and winding drum, respectively.

6. A crane comprising a carriage, a jib, a shaft on which the jib is pivotally mounted, racks carried by the said carriage, pinions on the said shaft in mesh with the said racks, means for rotating the shaft, a roller on the jib spaced apart from the pivotal support of the jib, a track for the said roller arranged divergently with respect to the said racks, a motor on the carriage, a winding drum rotatably mounted on the jib shaft, driving shafts geared to the said motor and

having the said frame slidably mounted thereon, and gearing transmitting motion from the said shafts to the frame and winding drum, respectively.

7. A crane comprising a carriage, a jib, a shaft on which the jib is pivotally mounted, racks carried by the said carriage, pinions on the said shaft in mesh with the said racks, a frame in which the said shaft is mounted, a driving shaft arranged parallel to the racks and having the said frame slidably mounted thereon, gearing connecting the said shafts, a winding drum rotatably mounted on the jib shaft, a second driving shaft arranged parallel to the racks and having the frame slidably mounted thereon, gearing connecting said second driving shaft to the winding drum, a roller on the jib spaced apart from the pivotal support of the jib, and a track for the said roller arranged divergently with respect to the said racks.

8. A crane comprising a carriage, a jib, a shaft on which the jib is pivotally mounted, racks carried by the said carriage, pinions on the said shaft in mesh with the said racks, a frame in which the said shaft is mounted to rotate, a driving shaft arranged parallel to the said racks and having the frame slidably mounted thereon, a worm carried by the frame and mounted on the said driving shaft to rotate therewith and slidably thereon, a worm wheel fast on the jib-supporting shaft and in gear with the said worm, a winding drum rotatably mounted on the jib-supporting shaft, a second driving shaft arranged parallel to the said racks and having the frame slidably mounted thereon, a second worm carried by the frame and mounted on the said second driving shaft to rotate therewith and slidably thereon, a worm wheel coupled to the winding drum and in gear with said second worm, a roller on the jib spaced apart from the pivotal support of the jib, and a track for the said roller arranged divergently with respect to the said racks.

9. A crane comprising a carriage, racks carried by the said carriage, a jib, a shaft on which the jib is pivotally mounted, a frame carrying the said shaft, pinions on the said shaft in mesh with the racks carried by the carriage, a driving shaft arranged parallel to the said racks and having the frame slidably mounted thereon, a worm carried by the frame and mounted on the said driving shaft to rotate therewith and slidably thereon, a worm wheel fast on the said jib supporting shaft and in gear with the said worm, a roller on the jib spaced apart from the pivotal support of the jib, and a track for the said roller arranged divergently with respect to the said racks.

10. A crane comprising a carriage, a jib, a winding drum, a shaft on which the jib

and drum are mounted, a motor on the carriage, a track along which the shaft is movable, a gearing connection between the motor and the shaft to move the said shaft along its track, and a gearing connection between the motor and the winding drum.

11. A crane comprising a carriage, a jib, a winding drum, a shaft supporting the jib and the drum, a motor on the carriage, pinions on the shaft, racks on which said pinions travel when the shaft is rotated, a gearing connection between the motor and the shaft to rotate the latter, and a second gearing connection between the motor and the drum to rotate the latter independently of the movement of the shaft when the pinions travel along the racks.

12. A crane comprising a carriage, a jib, a winding drum, a shaft supporting the jib and drum, a frame in which the shaft 20 is mounted to rotate, pinions on the shaft, racks on which said pinions travel when the shaft is rotated, driving shafts on which the frame is slidably mounted, a worm carried by the frame and rotated by one of 25 the driving shafts, a worm wheel fast on the jib-supporting shaft and in gear with the said worm, a second worm carried by the frame and rotated by another of the driving shafts, and a worm wheel carried by the 30 winding drum and in gear with the said second worm.
